UNITED STATES PATENT OFFICE.

FREDERICK G. OSBORN, OF NEWARK, NEW JERSEY.

WRENCH.

SPECIFICATION forming part of Letters Patent No. 309,084, dated December 9, 1884.

Application filed March 24, 1884. (No model.)

To all whom it may concern:

Be it known that I, FREDERICK G. OSBORN, a citizen of the United States, residing at Newark, in the county of Essex and State of New Jersey, have invented certain new and useful Improvements in Wrenches, of which the following is a specification, reference being had therein to the accompanying drawings, in which—

10 Figure 1 is a view of a portion of a side of my wrench, and Fig. 2 is a similar view of the same, showing the movable jaw in section.

This invention has relation to improvements in that class of wrenches known as 15 "sliding-jaw wrenches;" and it consists in the construction and novel arrangement of devices, as will be hereinafter more fully set forth, and particularly pointed out in the claim appended.

20 Referring by letter to the accompanying drawings, A indicates a wrench-shank, which may be of any approved construction, having the usual fixed head, a.

B indicates the sliding or box jaw, having 25 a recess in its under portion opening into the slot for the passage of the wrench-shank, forming a front and rear wall, h h. Pivoted within this recessed portion to the side walls of the jaw by means of a bolt, c, is a pawl-

30 lever, D. This pawl-lever has a series of teeth on its forward upper side, which incline upwardly and rearwardly to engage teeth of a similar contour of the shank A. The teeth of the lever D are held in engagement with the 35 teeth of the shank by means of a spiral spring, d, which is seated in an annular recess, e, in the said movable jaw, as shown. The pawl-lever D is also provided at its rear end with a thumb-post, E, which extends through an aperture in the rear portion of the said movable

40 jaw.

The aperture F in the pawl-lever D for the passage of the pivot-bolt c may be either elongated or a sufficient diameter annularly larger than the pivot-bolt to allow a slight play of 45 the said pawl-lever back and forth, so that when the movable jaw is adjusted on a nut or the like the strain during operation is removed from the pivot-bolt and transmitted to the forward wall, h, of the jaw B by the inner face, h', of the same coming in engagement with the head g of the pawl-lever. By this construction it will be perceived that when power is applied to the engaging face of the movable jaw its forward inner face wall, h', will engage the head g of the pawl-lever, thereby forcing its teeth securely in engagement with the teeth of the shank A, which will prevent any possibility of the jaw B slipping upon the shank during operation should the spring d, through weakness or otherwise, fail to keep the teeth of the pawl in engagement with the teeth of the shank.

Having thus described my invention, what I claim as new, and desire to secure by Letters 65 Patent, is—

In a wrench, the combination, with the shank A, constructed as described, of the box-jaw B, the pawl-lever D, having the thumb-post E, and pivoted within the said box-jaw, 70 the spring d, seated in the recess e, and the pivot-bolt c, the aperture F of the said pawl-lever being enlarged, as shown, whereby the said lever may be allowed a slight movement back and forth upon the pivot-bolt, to bring 75 the forward wall, h', of the box-jaw in engagement with the head g of the pawl-lever, substantially as and for the purposes specified.

FREDK. G. OSBORN.
